UNITED STATES PATENT OFFICE.

FLOYD W. SCHOOLEY, OF CHICAGO, ILLINOIS.

CHECK HOLDER.

Application filed May 11, 1922. Serial No. 560,138.

To all whom it may concern:

Be it known that I, FLOYD W. SCHOOLEY, a citizen of the United States, and a resident of Chicago, in the county of Cook and State 5 of Illinois, have invented a new and useful Improvement in Check Holders, of which the following is a full, clear, and exact description.

My invention relates to improvements in 10 check holders, and it consists in the combinations, constructions and arrangements herein described and claimed:

An object of my invention is to provide 15 a device of the character described in which positive means is provided for preventing the pad of checks from slipping out of the holder when the holder is held vertically.

A further object of my invention is to provide a device of the character described 20 in which a portion of the check is removed by manually drawing the check through a shearing member.

A further object of my invention is to provide a device of the character described, 25 the constructions of which permits the checks to be easily grasped one at a time for removal from the pad.

A further object of my invention is to provide a device of the character described, 30 which is extremely simple in construction, which may be easily and cheaply manufactured, and which is thoroughly practical for the purpose intended.

Other objects and advantages will appear 35 in the following specification, and the novel features of the invention will be particularly pointed out in the appended claims.

My invention is illustrated in the accompanying drawings, forming part of this application, in which—

Figure 1 is a perspective view of an embodiment of my invention.

Figure 2 is an end elevation of the mechanism illustrated in Figure 1, and

Figure 3 is a diminutive end elevation of the mechanism illustrated in Figure 1.

In carrying out my invention, I make use of a metal body member 1 which is substantially U-shaped in cross section. One of 50 the side walls 2 of the body member 1 is in portion relatively higher than the opposite side wall 3.

The side wall 2 has riveted thereto a spring metal shearing member 4. The other 55 end of the shearing member 4 is brought to a point as shown at 5 and the edges of the

outer end 5 are sharp, the spring member being made by a die cutting process. The inherent spring properties of the spring member 4 tend to normally hold the member 60 in the position shown in Figure 1.

A pair of outwardly extending lugs 6 are formed on the outer surface of the wall 2 by shearing a portion of the wall and subsequently punching the sheared lug to 65 the position shown in the drawing. The lugs 6 provide means for limiting the lateral movement of a check as shown at 7 as it is placed upon the surface of the wall 2 in a manner hereinafter described. The rearward portion of the wall 2, as shown at 70 8, is relatively the same height as the wall 3. The portion 8 of the wall 2 and the wall 3 are each provided with integral inwardly extending tongues 9. The tongues 9, as reference to Figure 2 will show, provide means for retaining a pad of checks 10, such as shown in dotted lines in Figure 1, in the check holder, the tongues 9 being inserted between the superposed checks. Integral 75 upwardly extending stop members 11 are provided at one end of the body member 1 and serve as a means for limiting the longitudinal movement of the pad 10 when placed in the check holder.

The body member 1 is provided with an outwardly extending fastening ring 12, by means of which a chain, as shown at 13, may be secured and serves as a supporting member for the check holder. Ordinarily, 80 the chain 13 is attached to the dress of the user.

The outer edge of the body member 1, as shown at 14, is at an angle to the side walls 2 and 3 thereof, the edge 14 gradually sloping rearwardly from the wall 2 to the wall 3. The purpose of this construction is to enable the user to place a finger beneath the pad 10 and thus move the checks upwardly at their outer extremities so that 85 they may be easily grasped for removal individually from the pad.

From the foregoing description of the various parts of the device, the operation thereof may be readily understood. In the 100 ordinary type of check holders in common use, the pad 10 is held in place by tongues somewhat similar to the tongues 9, and it is a common occurrence for the pad 10 to 105 slip out of the check holder unobserved and fall to the floor where it may be lost. In my present device, this disadvantage is entirely 110

obviated, since the provision of the stop members 11 serves as a means to positively prevent longitudinal movement of the pad 10 after it has been inserted in the holder. 5 It should be noted that the pad is bound at its rearward end, as shown at 15, so that the forward longitudinal movement would be obviously impossible.

In use, a waiter, or whoever may use the 10 check, removes one of the checks from the pad 10 and places it in the position shown in Figure 3 so that one of its edges abuts the lugs 6. He then moves the check longitudinally until the desired numeral is 15 opposite the point 5. The spring shearing member 4 is then manually pressed closely upon the check 7 and the check is drawn upwardly over the point 5 of the member 4. This action serves to shear away a portion 20 of the check 7 and the sheared portion indicates to the cashier what amount the customer is to pay.

I claim:

1. A device of the character described 25 comprising a body member adapted to receive a pad of checks having one end bound, said body member being substantially U-shaped, in cross section, a pair of integral diametrically opposed inwardly extending 30 tongues on the side walls on said body member adjacent the top thereof, and arranged

to lie between superposed checks in said pad to preclude the accidental movement of said pad in one direction, and integral inwardly extending stop members on said 35 body member at the top thereof for resisting movement of said pad longitudinally, said inwardly extending tongues being arranged to extend inwardly from the side walls of the body member sufficient to prevent the passage of the bound portion of said pad of checks thereby. 40

2. The combination with a pad of checks bound together at one end thereof, of a holder for said checks comprising a substantially flat body member having a stop member at one end thereof for resisting the movement of said check pad longitudinally in one direction, said body member being formed with side members arranged to lie 50 relatively close to the side walls of said check pad, and having a pair of diametrically opposed inwardly extending tongues thereon arranged to lie between superposed checks in said pad and to extend toward 55 one another for a distance sufficient to preclude the passage thereby of the bound portion of said checks, said tongues being disposed on said side portions adjacent that portion of said body member on which said stop members are disposed.

FLOYD W. SCHOOLEY.
